UNITED STATES PATENT OFFICE.

FREDERICK A. PRESTON, OF HIGHLAND PARK, ILLINOIS, ASSIGNOR TO THE P. & M. CO. OF CHICAGO, ILLINOIS, A CORPORATION OF ILLINOIS.

ANTICREEPER.

1,133,399.

Specification of Letters Patent. Patented Mar. 30, 1915.

Application filed March 31, 1913. Serial No. 757,792.

To all whom it may concern:

Be it known that I, FREDERICK A. PRESTON, a citizen of the United States, residing at Highland Park, in the county of Lake 5 and State of Illinois, have invented new and useful Improvements in Anticreepers, of which the following is a full, clear, concise, and exact description, reference being had to the accompanying drawing, forming a 10 part of this specification.

My invention relates to anti-creepers for railroad rails, such devices being known also as rail anchors.

In devices hitherto constructed and proposed of the type wherein the anti-creepers maintains its hold by reason of pairs of jaws which grip the rail base with a firm frictional hold, the construction is usually such that when the rail tends to creep, said jaws 15 are moved inwardly toward the longitudinal axis of the rail so as to increase their frictional hold. To secure this action such rail anchors have been constructed, generally speaking, in two forms. In one form there 20 are two or more parts which engage each other in such a manner that when they slide one on the other longitudinally, the pairs of jaws are moved inwardly to grip the rail base more firmly. In the other form the rail 25 anchor comprises a one piece yoke having jaws spaced apart a distance greater than the width of the rail base whereby the rail anchor may be located on the rail base properly, but in order to cause both pairs of said 30 jaws to grip said rail base, it is necessary to skew the rail anchor to a diagonal position, that is, with the jaws arranged one pair considerably in advance of the other. In this 35 position, although said pairs of jaws are not brought closer together, they are each brought closer to the central axis of the rail.

The object of my present invention, generally speaking, is to provide a rail anchor which maintains its hold on the rail base by 40 friction due to its initial grip thereon, there being no subsequent movement which increases or tends to increase said grip.

The subsidiary objects are to provide a one piece rail anchor adapted to act in this manner, to provide a rail anchor of this character which shall be of comparatively simple construction and lend itself to economical manufacture, and to provide a rail anchor which shall effectively maintain its

hold on the rail base, regardless of whether 55 or not the pressure of the rail anchor against the cross-tie is maintained.

Other objects and advantages may be readily inferred without specific reference thereto, from a consideration of the detailed 60 description hereinafter given of several forms of the invention.

In the accompanying drawings I have illustrated the several forms referred to. The invention is not limited to the constructions illustrated, however, as it may be embodied in other forms.

In said drawings Figure 1 is a top plan of one form of rail anchor, showing the same as it is being applied to the rail base; Fig. 2 70 is an end elevation thereof; Fig. 3 is a top plan view of said rail anchor in the position which it finally assumes upon the rail base; Fig. 4 is an end elevation thereof; Fig. 5 is 75 a side elevation of this form of anti-creepers; Fig. 6 is a section through one of the pairs of jaws; Fig. 7 is a top plan view of another form of anti-creepers; and Fig. 8 is a top plan view of a combined tie-plate and anti-creepers. 80

The rail anchor in the various forms illustrated comprises a pair of jaws 1, 2, each adapted to grip the rail base firmly when forced thereon, said pairs of jaws being provided with a connecting member which is 85 preferably integral therewith whereby a one piece construction results. In Figs. 1 to 7 inclusive, the connecting member has the form of a yoke 3 arranged at one end of said jaws, although it may be otherwise located 90 with respect thereto. Said yoke has a bearing face 4 adapted to bear against the cross-tie 5, thus transmitting thereto the thrust due to the creeping tendency of the rail. Said yoke is also provided preferably with 95 a reinforcing flange or web 6 integrally united thereto.

The pairs of jaws 1 and 2 are arranged initially with their inner vertical walls 7, 8 flaring outwardly, as shown in Fig. 1, for 100 example. The distance between the inner edges of said pairs is preferably somewhat less than the width of the rail base. In carrying out this construction said edges are arranged substantially parallel to each 105 other, as shown in Fig. 1, although this feature is not essential. The rail anchor is applied to the rail, as may be inferred read-

ily from Fig. 2, by hooking one pair of jaws over the rail base and then hooking the other jaw over the opposite side, said jaws overlying the rail base only a slight amount, just sufficient to keep the rail anchor from falling off at this stage of the operation. It is for this reason that it is desirable to provide the jaws with the parallel inner edges above referred to. In order to cause said jaws to take a firm hold on the rail base, they are driven toward each other by hammer blows until they assume the position shown in Figs. 3 and 4. This operation, of course, causes the structure to bend or give at some point, most of the bending taking place at or near the opposite ends of the yoke 3. The rail anchor being constructed preferably of malleable iron or other material having similar properties as far as bending is concerned, this deformation of the structure may be effected without danger of breaking it. The opening between each pair of jaws, as shown in Fig. 6, is preferably of a somewhat less angle initially than the corresponding angle made by the upper and lower face of the rail base. Furthermore, the vertical inner walls 7 and 8 of said jaws are preferably of slightly less height than the corresponding vertical outer edge of the rail base. Accordingly, when the jaws are driven or forced onto the rail base, they are sprung somewhat and hence maintain a very firm frictional hold on the top and bottom of the rail base. The design is preferably such that the pressure or gripping action of each jaw is substantially uniform at all points. That is to say, the jaw is sprung the most at points remote from the vertical wall 8, at which points the lever arm is the longest, and is sprung the least at points where the lever arm is shorter, thereby tending to give substantially uniform "moments". As the rail tends to creep to the left as viewed in Fig. 5, the pressure may cause the yoke 3 to bend somewhat (see dotted line position in said figure), in which case the flange or web 6 is brought to bear against the base of the rail. Said flange is constructed so as to give normally a slight clearance between itself and the rail base to facilitate assembling the device on the rail. The said web may be brought into firm bearing engagement with the rail base initially by driving the entire rail anchor toward the tie without waiting for the creeping action to cause the bending. Said web by bearing directly against the rail base has a binding effect thereon, this action serving to assist somewhat the resistance offered to the creeping thrust. The area of the jaws in frictional engagement with the rail base is of considerable extent, due mainly to the comparatively great length of the jaws, as will be apparent from the drawings, and after a rail anchor has once

been properly applied the jaws rust in position in time, whereby they become practically united to the rail base.

In the form of rail anchor shown in Fig. 7 the jaws are provided with a yoke 9, which is used to aid in forcing the pairs toward each other when the rail anchor is being applied to the rail. In the first form of rail anchor described, it is necessary to drive the pairs of jaws toward each other by striking on the reinforcing flanges. The most convenient way is to hammer inwardly both pairs simultaneously by the use of two hammers. In the form shown in Fig. 7, however, the yoke 9 is fitted over the ends of the jaws and driven toward the tie, whereupon said yoke serves to draw said jaws inwardly until they have the desired firm frictional hold on the rail base.

In the form of device shown in Fig. 8 the jaws are constructed as an integral part of a tie-plate 10. The yoke which is integrally united to the jaws may bear directly against the tie to aid in resisting creeping, as in Fig. 5, or, if it is desired to rely entirely on the spikes 11 which secure the tie-plate to the tie, the said yoke may clear the tie. The device shown in Fig. 8 is adapted to prevent creeping in either direction, as the movement of the rail is not relied upon to increase the grip of the rail anchor thereon.

Among the many advantages which are inherent in the devices disclosed it may be mentioned that the one piece construction makes the device easy to handle and easy to apply to the rail. The rail anchor can never work loose and drop from the rail even if the rail should have a rearward movement due to a contraction caused by cold or due to a reversal of traffic.

It is to be understood, of course, that the invention is not to be limited to the particular embodiments thereof described and illustrated or to the details thereof, as various changes may be made without departing from the spirit of the invention as expressed in the appended claims.

Having thus described my invention, what I claim as new and desire to secure by Letters Patent of the United States is:

1. An anti-creeper comprising oppositely arranged pairs of jaws, each pair adapted to wedgingly engage an edge of a rail base, said pairs of jaws being connected by means integral therewith, and being spaced apart sufficiently to permit of their being assembled on a rail with the base flanges between them whereby they may be brought to final gripping position on the rail base by being forced toward each other, said structure being deformed by such operation and given a permanent set.

2. An anti-creeper comprising oppositely arranged pairs of jaws each pair adapted to wedgingly engage an edge of a rail base and

- a non-resilient yoke integrally connected thereto and maintaining said pairs of jaws at such a distance from each other as to cause a fit thereof on the rail base in such 5 manner that a firm grip thereon is obtained only by forcing the jaws toward each other so as to deform said structure and give it a permanent set.
3. An anti-creeper comprising a yoke 10 provided at each end with rail gripping jaws integral therewith, one of said jaws extending substantially horizontally from said yoke at an angle thereto so that it may be caused to operatively engage a rail base only 15 by being driven toward the rail base so as to vary said angle and deform the structure.
4. A one-piece anti-creeper having a plurality of pairs of jaws for gripping a rail base on opposite sides of the rail, a portion 20 of the structure between said pairs of jaws being capable of permanent distortion to bring said pairs of jaws into their final rail-gripping relation to each other and to the rail base.
- 25 5. A one-piece anti-creeper having a plurality of pairs of jaws adapted to operatively grip a rail base at opposite sides of the rail, a portion of said structure between said pairs of jaws being capable of permanent distortion to bring one of said jaws into final wedging engagement with a rail base.
6. A one-piece anti-creeper comprising a transverse element beneath the rail base having 35 means at one end for operatively gripping the upper and lower faces of a rail base and having at the other end a rearwardly projecting portion bendable inwardly to bring it into permanent wedging 40 engagement with the upper surface of a rail base.
7. A one-piece anti-creeper having a tie abutting surface extending forwardly and downwardly so as to engage a tie only on a 45 surface substantially below the base of a rail and having two pairs of rearwardly extending jaws which diverge from each other and which may be made to grip the rail base by deforming the structure so as to decrease 50 the angle between said pairs of jaws.
8. An anti-creeper comprising a transverse element arranged beneath the rail base, a pair of jaws integral with each end of said element, the inner vertical walls of said 55 pairs of jaws normally diverging from each other whereby in order to bring said walls against the opposite sides of the rail base it is necessary to bend the structure.
9. An anti-creeper comprising a yoke, a pair of rail gripping jaws at each end thereof and integral therewith, a tie-abutting face on said yoke and a reinforcing web integral with said yoke, said web extending beneath the rail base and normally clearing the same, but being adapted to bear against 65 the same when the yoke bends.
10. An anti-creeper comprising means arranged transversely beneath the rail base with pairs of jaws at opposite ends thereof for gripping the rail flanges, a tie-abutting 70 face thereon to resist creeping, and a web integral therewith and arranged substantially parallel to the longitudinal axis of the rail, said web normally clearing said rail.
11. A rail anchor comprising two pairs of rail-gripping jaws arranged opposite to each other and integrally united by a non-resilient connecting member beneath the rail base, the angle of the jaws of each pair being 80 slightly less than the angle of the corresponding section of the rail base.
12. In an anti-creeper, two pairs of jaws, each requiring to be sprung somewhat when forced to operative position on the rail base, 85 said pairs of jaws having a holding area on said base which is relatively long as compared to its width, and means connecting said pairs of jaws to prevent their moving apart, said jaws adhering to said rail base 90 in service independently of any holding thrust developed by a creeping tendency of the rail.
13. A rail anchor consisting of a single malleable casting formed at opposite ends 95 with jaws adapted to engage the opposite edges of the base flange of a railroad rail, the portion of said casting between said jaws being adapted to be bent to a permanent set so as to cause said jaws to operatively 100 grip said base flanges.
14. A rail anchor comprising a rail gripping member provided with means for engaging opposite sides of a railroad rail, a portion of the device carrying one of said rail engaging means being bendable to a permanent set after the device has been applied to a rail so as to bring the rail engaging means carried thereby into non-detachable engagement with the rail.
- In witness whereof, I have hereunto subscribed my name in the presence of two witnesses.

H. C. PARKER.

It is hereby certified that in Letters Patent No. 1,133,399, granted March 30, 1915, upon the application of Frederick A. Preston, of Highland Park, Illinois, for an improvement in "Anticreepers," errors appear in the printed specification requiring correction as follows: Page 1, line 82, for the words "a pair" read *two pairs*; page 2, line 38, for the word "remote" read *removed*; and that the said Letters Patent should be read with these corrections therein that the same may conform to the record of the case in the Patent Office.

Signed and sealed this 20th day of April, A. D., 1915.

[SEAL.]

J. T. NEWTON,

Acting Commissioner of Patents.
